United States Patent

Des. 239,745
Patented May 4, 1976

239,745

CHAIR

Donald B. Gold, San Rafael, Calif., assignor to
K.I.S.S. Industries, San Rafael, Calif.

Filed Sept. 3, 1974, Ser. No. 502,604

Term of patent 14 years

Int. Cl. D6—01

U.S. Cl. D6—49

FIG. 3.

FIG. 2.

FIG. 1.

FIG. 4.

FIG. 7.

FIG. 6.

FIG. 5.

FIG. 8.

FIG. 1 is a front and left side perspective view of a first embodiment of my new chair design;

FIG. 2 is a right side elevational view thereof;

FIG. 3 is a back side elevational view thereof;

FIG. 4 is a bottom plan view thereof;

FIG. 5 is a view similar to FIG. 1, but showing a second embodiment of my new chair design; and

FIGS. 6 through 8 are views similar to FIGS. 2 through 4, respectively, but showing the second embodiment of my new design.

I claim:

The ornamental design for a chair, substantially as shown.
